CLAIM

The ornamental design for a pendant pull for a slide fastener, substantially as shown and described.

DESCRIPTION

FIG. 1 is a front elevational view of a pendant pull for a slide fastener showing my new design;

FIG. 2 is a typical side elevational view of FIG. 1;

FIG. 3 is a cross section taken along the line 3—3 of FIG. 1;

FIG. 4 is a top plan view of FIG. 1; and

FIG. 5 is a bottom plan view of FIG. 1.

FIG. 3
